UNITED STATES PATENT OFFICE.

ALEXANDER GODFREY, OF HAVERHILL, MASSACHUSETTS; ANNIE E. GODFREY AND ARTHUR C. MURPHY, BOTH OF HAVERHILL, MASSACHUSETTS, EXECUTORS OF SAID ALEXANDER GODFREY, DECEASED.

LAST.

Application filed July 20, 1921. Serial No. 486,214.

To all whom it may concern:

Be it known that I, ALEXANDER GODFREY, a citizen of the United States of America, and a resident of Haverhill, in the county of 5 Essex and Commonwealth of Massachusetts, have invented certain new and useful Improvements in Lasts, of which the following is a specification.

This invention relates to lasts for use in 10 the manufacture of boots and shoes, and more particularly to that class of lasts commonly known as hinged or collapsible lasts. Among the objects of this invention is the 15 production of a hinged last, of such construction and arrangement as to enable the manufacturer to use it in all the various operations of shoe manufacture, with the possible exceptions of the beating out and heel-ing operations. For these two operations it 20 is preferred to use a well known form more stoutly constructed, but of the same size and shape as the one which it replaces, known as the "maker".

It is also an object of this invention to 25 produce a hinged last that may be removed from the shoe at any stage of the manufac-ture thereof without causing detrimental strains to be exerted upon the shoe when the last is withdrawn therefrom, and which 30 will not in any way distort the upper, after having been carefully lasted and pulled over, during the aforesaid withdrawal.

It is a further object of this invention to 35 produce a hinged last that is simple in struc-ture and arrangement and yet durable; and that is capable of being held in locked po-sition when extended and in the shoe, and readily unlocked preparatory to removal therefrom.

40 Unlike the hinged last at present in use, the herein disclosed last actually shortens when the heel part is moved toward the forepart and does so immediately upon said movement of the heel part, and consequently 45 the entire shoe is relieved of the strains in-incident to the lasting operations and the last may be slightly shifted bodily towards the heel and thereafter wholly withdrawn from the shoe, leaving it without having caused either strain or distortion thereto.

50 This last mentioned feature is not present in the hinged lasts now in use. While it is true that they shorten eventually upon re-moval from the shoe, they do so at the

wrong time; in fact they lengthen first and 55 in so doing often times cause the upper at the forepart to split or the heel stitching to part, (sometimes both) and thereafter they shorten when the damage has been done. This is a condition which the pres-60 ent invention has actually overcome and to that end the invention consists in certain novel features of construction and arrange-ment of parts which will be fully understood from a description of the drawings and the 65 claims hereinafter given.

Of the drawings:

Figure 1 represents in side elevation a last having the present invention applied thereto.

Figure 2 a view similar to Fig. 1 with the 70 last partially broken away to expose the fore and heel part connectors and locking mechanism in elevation.

Figure 3 a section on the line 3—3 Figure 2.

Figure 4 a section on the line 4—4 Figure 2.

Figure 5 an enlarged view of the slidable lock plate as seen in Figure 4.

Figure 6 a section on the line 6—6 Figure 5.

Figure 7 a section on the line 7—7 Figure 5.

Figure 8 is a perspective view of one of the link-like plates that retain the fore and 85 heel parts in operative position.

Figure 9 a view similar to Figure 2 show-ing the heel part as having been moved up-wardly and forwardly preparatory to the removal of the last from a shoe.

Figure 10 a view similar to Fig. 9 to show how the last may be moved bodily toward the heel to relieve all strain from the shoe preparatory to the withdrawal of the last therefrom.

Like characters designate like parts throughout the several figures of the draw-ings.

Referring to the drawings:

The last 10 which may be of the desired 100 size and shape is composed of a forepart 11 and heel part 12 so constructed and ar-ranged as to be swung relatively toward and from each other through the medium of connector plates about to be explained.

Secured to the heel part 12 in a slot 13 provided therefor by the removable pins 14, are the plates 15 which extend forwardly

into a slot 16 in the forepart 11. Slots 17 in the said plates 15 struck on an arc, the center of which is not visible in practice but located approximately at 18, are adapted 5 to receive the limiting pin 19 which is stationary with the forepart 11. The plates 15 are primarily intended to form the retaining means for the fore and heel parts and, in conjunction with another simple device 20, arcuate in shape for the major portion thereof and adapted to be held rigidly with relation to the forepart 11 by reason of the upward extension 21 abutting the end wall of slot 16 and the pin 22, they form 10 a simple and effective sliding connection for the two parts.

The plates 15, one of which is shown in Fig. 8, are provided with grooves 40, which are concentric with the slots 17, and adapted 20 to receive the device 20 which functions as a track upon which the heel part is guided in its movements, and also as one member of a locking means to hold the last in extended position.

25 It will thus be seen that the plates 15 and device 20 act in conjunction to form a sliding connection that is simple in construction, cheap to manufacture and durable.

While the plates 15 are herein shown as 30 two in number, it is obvious that it is possible to construct this portion of the hinge of one piece stamped out and formed to perform the function as at present.

The device 20 is provided with a notch 35 23 adapted to be entered by a slidable plate 24 for the purpose of locking the two parts in extended position.

The said plate 24 is held in sliding position by means of the beveled edges 25 being 40 overlapped by the undercut edges 26 of a plate 27 secured to the heel part 12 by means of screws 28.

Pivoted to the heel part at 29 is a latch member 30 one end of which 31 extends 45 forwardly through an opening 32 in the plate 27 and engages the upper end of a small opening 33 in the plate 24. Normally the plate 24 is under the control of a spring 34, one end of which bears against the tongue 35 struck from the plate 24, an elongated slot 36 being provided therefor in the plate 27. The latch member 30 has a rearwardly extending portion which terminates in the inclined cam shape portion 37 adapted 55 to be engaged by a hand tool 38 or similar device which may be attached to a machine or last removing device or jack.

The said member 30 is so constructed as 60 to present its cam portion 37 to the path of the tool 38 which is adapted to enter the hole 45 and be guided thereby. The entrance of the said tool into the hole causes it to contact with and depress the cam 37 and consequently raises the plate 24 against 65 the action of the spring 34. The cam 37 is

so arranged as to be swung out of the path of the tool 38 at the completion of the unlocking movement of plate 24 and the tool 38 will be free to continue its movement to finally seat itself in the hole 45 if desired. 70

It will be understood that the herein disclosed last is intended to be used in the majority of operations incident to the manufacture of a complete shoe which includes the treeing operation. It therefore insures 75 the production of a finished shoe that retains its original intended shape, free from the usual defects and weaknesses caused by strains in removing the last from the shoe and in general presenting a much better and 80 durable shoe and entirely eliminating the great loss caused by the removal of improperly constructed lasts from the finished shoe.

Viewing Figures 9 and 10 it will be readily 85 seen how the last may be removed from the shoe, the dotted lines 50 indicating the shoe outline and the broken lines 51 (see Fig. 9) indicate the path taken by the heel part in its upward and forward movement. 90

It is obvious that the center of swing of the heel part is so located as to cause a simultaneous upward and forward movement to said heel part, which instantly relieves pressure throughout the shoe. 95

To further reduce strains and insure ease of removal, the last may be slightly shifted rearwardly in the shoe before the removal thereof if deemed necessary, and as clearly shown in Figure 10 the shoe is entirely relieved of pressure of the last and may now be removed without distorting the shoe in the slightest degree. 100

In order to present a smooth surface to the last and to facilitate in the swing of the parts thereof, the two parts are shaped as at 105 55 and 56 to conform to the movement given by the connector guide members 15 and 20, the center of swing 18 being located at approximately the junction of the planes of 110 the bottom of the heel part 12 and the rear face 57 of the forepart 11. It will be understood that the heel part plane is one that intersects the forward and rear tips of the heel. 115

It is not the intention to limit this invention to the precise construction and arrangement herein shown as it is obvious that various changes may be made without departing from the spirit and scope of the 120 invention.

Having described the invention I claim:

1. In a last of the class described, the combination of a two-part last adapted to be hinged, the pivotal center of which is approximately in a plane with the bottom of the heel part, of a hinge comprising a member fast with the forepart and a member fast with the heel part; guiding means in one 125 of said members adapted to be entered by 130

the other member; means coacting with said heel part member adapted to further aid in the guidance of said member; and means coacting with one of said members to lock the 5 said last in extended position.

2. In a last of the class described, the combination of a two-part last adapted to be hinged, the pivotal center of which is approximately in a plane with the bottom of 10 the heel part, of a hinge comprising an arcuate member fast to said forepart, a two-part member having arcuate grooves there-in adapted to receive and be guided by said arcuate member; said two-part member having a slot adapted to receive a pin fast in 15 said forepart whereby said heel part is retained in operative position with said forepart; a locking device coacting with said arcuate member adapted to hold the last in extended 20 position; and means to disengage said locking means at will.

3. In a last of the class described, the combination of a two-part last adapted to be hinged, the pivotal center of which is located 25 approximately in a plane with the bottom of the heel part; of a hinge comprising an arcuate member fast with said forepart; a two-part member fast with said heel part; said two-part member having grooves adapted 30 to receive and be guided by said arcuate member; said two-part member also having a slot concentric with said arcuate member; a pin in said forepart coacting with said slot to retain said fore and heel parts in working 35 engagement; said arcuate member having a notch; a locking plate slidable on said heel part adapted to at times engage said notch; and means to disengage said plate from said notch at will.

4. In a last of the class described, the combination of a two-part last adapted to be hinged, the pivotal center of which is located approximately in a plane with the bottom of the said heel part, of a hinge comprising an 45 arcuate member fast with said forepart; a two-part member fast with said heel part, and with the forepart by a slot and pin connection; said two-part member having a groove adapted to receive said arcuate member 50 and guide said two-part member thereby; said arcuate member having a notch adapted to engage a slidable locking plate; a slidable locking plate; a plate secured to said heel part and adapted to retain said 55 slidable plate in operative position; means to normally retain said slidable plate in locking position; and means to disengage said locking plate from said notch at will.

5. In a last of the class described, the combination of a two part last adapted to be hinged, of a fore part having a slot therein; a hinge member secured in said slot and projecting therefrom; means to secure said member in said slot; said member having a finger projecting therefrom, adapted to abut 60

the end wall of said slot and thereby prevent pivotal movement of said member in one direction; a heel part having a slot in which a second hinge member is secured and projects therefrom into the slot of said fore part; means to retain said member in sliding engagement with said fore part; means forming part of said second member adapted to guide said first member and prevent pivoted movement thereof in another direction; means to lock said last in extended position; and means to disengage said locking means at will. 70

6. In a last of the class described, the combination of a two part last adapted to be hinged, the pivotal center of which is approximately in a plane with the bottom of the heel part; of a hinge member adapted to be secured in a slot of said fore part by a pin, 75 said member having a projection confined in said slot and adapted to abut the end wall thereof, whereby pivotal movement of said member in one direction is prevented; a second hinge member rigidly secured in a slot of the heel part and projecting into the slot 80 of said fore part, said second member being so constructed and arranged as to guide said first member and prevent pivotal movement thereof in another direction; means co-acting 85 with said first member to lock said last in extended position; and means to disengage said locking means at will. 90

7. In a last of the class described, the combination of a two part last adapted to be hinged, the pivotal center of which is approximately in a plane with the bottom of the heel part; of a hinge member adapted to be secured in a slot of said fore part by a pin, 95 said member having a projection confined in said slot and adapted to abut the end wall thereof, whereby pivotal movement of said member in one direction is prevented; a second hinge member rigidly secured in a slot of the heel part and projecting into the slot 100 of said fore part, said member being so constructed and arranged as to guide said first member and prevent pivotal movement thereof in another direction; means to retain said second member in sliding engagement with said fore part, said means including a pin; means co-acting with said first member to lock said last in extended position; and means to disengage said locking means at will. 110

8. A last adapted to be collapsed, having 120 aligned slots in the abutting surfaces of the fore and heel parts thereof; each part having a member fast thereto adapted to be guided by the other member in approximately the direction of its length, each member of a 125 part extending into the slot of the other part; means located in one of the parts whereby one of said members is further slidingly guided; and means to lock said parts in extended position. 130

9. A last adapted to be collapsed, having slots in the abutting surfaces of the fore and heel parts respectively; a member fast in the slot of the heel part; a member fast in the slot of the fore part; means whereby each of said members guides the other; one of said members having slot and pin connection with one of said parts; locking means carried by said heel part adapted to coact with the member fast with the fore part to positively lock said parts in extended position; and means to unlock said locking means.
10. In a last adapted to be collapsed, having a member fast in the fore part and a

member fast in the heel part, each member adapted to overlap the other, whereby each will form a bearing for the other during relative movements therebetween; one of said members having slot and pin connection with one of said parts whereby said parts are slidingly held in operative relationship, said slot being parallel to the line of last collapsing movement; and means coacting with one of said members to lock said parts in extended position.

Signed by me at Haverhill, Massachusetts, this 15th day of July, 1921.

ALEXANDER GODFREY.
